Term of patent 14 years

(Cl. D87—3)

T 1 □ S.

FIG. 1 is a side elevational view of a handbag or similar article showing my new design, the side opposite being identical thereto;

FIG. 2 is an end elevational view thereof, the end opposite being identical thereto;

FIG. 3 is a sectional view on an enlarged scale taken on line 3—3 of FIG. 1;

FIG. 4 is an enlarged elevational view of one of the units comprising the pattern thereof; and

FIG. 5 is a perspective view of the handbag of FIG. 1.

The dominant features of the present design reside in the full line portions shown in the drawing, the broken lines on the sides of the design indicate a repeat or continuous pattern.

I claim:

The ornamental design for a handbag or similar article, substantially as shown and described.
